Primary Examiner — Cynthia R Underwood

(57) **CLAIM**

The ornamental design for a nesting canning jar, as shown and described.

DESCRIPTION

FIG. 1 is a front perspective view of a nesting canning jar;
 FIG. 2 is a front elevation view thereof;
 FIG. 3 is a rear elevation view thereof;
 FIG. 4 is left side elevation view thereof;
 FIG. 5 is a right side elevation view thereof;
 FIG. 6 is a top plan view; and,
 FIG. 7 is a bottom plan view thereof.
 The broken lines shown in the figures depict portions of the nesting canning jar that form no part of the claimed design.

1 Claim, 4 Drawing Sheets
